US0D1097555S

(12) **United States Design Patent** (10) **Patent No.:** **US D1,097,555 S**
(45) **Date of Patent:** **** Oct. 14, 2025**

(54) **BAG**

(71) Applicant: **LORO PIANA S.P.A.**, Quarona (IT)

(72) Inventor: **Raffaella Redaelli De Zinis**, Quarona (IT)

(73) Assignee: **LORO PIANA S.P.A.**, Quarona (IT)

(**) Term: **15 Years**

(21) Appl. No.: **29/761,838**

(22) Filed: **Dec. 11, 2020**

(30) **Foreign Application Priority Data**

Nov. 16, 2020 (EM) 008270169

(51) **LOC (15) Cl.** **03-01**

(52) **U.S. Cl.**

USPC **D3/245**

(58) **Field of Classification Search**

USPC D3/215-217, 232-233, 242-243,
D3/245-246, 273-274, 279, 289-290,
D3/301-302, 318-319

CPC .. A45C 3/06; A45C 3/00; A45C 13/02; A45F
3/02; A45F 3/04

(57) **CLAIM**

The ornamental design for a bag as shown and described.

DESCRIPTION

FIG. 1 is a perspective view of a bag;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The dashed-dashed broken lines represent portions that form no part of the claimed design.

The dashed-dot broken lines represent boundary lines between claimed and disclaimed portions of the design.

1 Claim, 7 Drawing Sheets
